UNITED STATES PATENT OFFICE.

HENRY MUELLER, OF PITTSBURGH, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

APPARATUS FOR FEEDING PULVERIZED FUEL.

Application filed January 28, 1923. Serial No. 614,961.

To all whom it may concern:

Be it known that I, HENRY MUELLER, a citizen of the United States, residing at Pittsburgh, county of Allegheny, and State 5 of Pennsylvania, have invented a new and useful Improvement in Apparatus for Feeding Pulverized Fuel, of which the following is a full, clear, and exact description.

The present invention relates broadly to 10 the art of pulverized fuel feeding, and more particularly to a method and apparatus whereby certain disadvantageous features of the prior art constructions are overcome.

15 It has heretofore been proposed to feed pulverized fuel by means of a single screw-conveyor. The difficulty with such constructions has been the lack of uniformity of feed and the tendency of the fuel to 20 continue to flow after the conveyor was stopped, due to the fact that the single screw-conveyor offered a continuous passage for the finely divided fuel. This tendency of the fuel to feed unevenly and to 25 continue to flow after the stoppage of the conveyor often produced what is known in the art as "flushing." To overcome this disadvantage of the single screw-conveyor, it has been proposed to provide a pair of 30 cooperating screws, as shown in the patent to Covert, No. 1,197,799, of September 12, 1916. This type of feeder, however, has been found in actual practice to offer numerous disadvantages, such as rapid wear- 35 ing of the parts, due to the constant grinding action of one screw upon the other, and relatively large power consumption, due to the necessity for rotating the screws at a relatively high speed while overcoming a 40 large amount of frictional resistance.

By the present invention the above mentioned and other disadvantages of the prior art constructions are overcome, an important object of the invention being to provide a fuel feeding system having a single 45 rotating feeding member provided with peripheral fuel receiving means adapted to continuously and uniformly receive and discharge fuel, together with an auxiliary air blast in contact with the discharge side of the rotating feeding member adapted to clean the fuel receiving means in the periphery of said member of fuel and fill the same

with air for aerating the fuel prior to delivery to said rotating member. 55

A further object of the invention is to provide a main air supply and an auxiliary air supply, the auxiliary air supply conveying the fuel in suspension from the discharge side of the rotating feeding member 60 and discharging into the main air supply in such manner that the latter acts as an ejector for the auxiliary air supply and the fuel carried in suspension therein.

Further objects and advantages of the invention will be apparent as the description proceeds. 65

The invention is illustrated in the accompanying drawings, in which:—

Figure 1 is a view showing my improved 70 fuel feeding apparatus in elevation, a portion of the furnace being shown in section.

Figure 2 is a vertical sectional view of the rotating feeding member and of the means for conveying the fuel to and from said 75 member, and also showing the driving connections for said member.

Figure 3 is a sectional view taken on the line III—III of Figure 2 and looking towards the right. 80

Figure 4 is a plan view of the rotatable feeding drum.

Figure 5 is a fragmentary sectional view showing the flexible connection between the auxiliary and main air conduits. 85

Figure 6 is a detail view of the flexible diaphragm forming part of the connection shown in Figure 5.

Referring to the drawings, 1 indicates a housing or casing having a hopper 2 connected with a fuel feeding chute 3. Journaled in suitable bearings in the casing 1 is a shaft 4 upon which is mounted a drum 5. The drum 5 is fixed to the shaft 4 by means of an integral projection 6 on the drum co-operating with a cut-away or faceted portion 7 of the shaft, so that the drum and shaft are affixed to each other against either relative rotational or longitudinal movement. 90

The ends of the drum 5 cooperate with bearings 8 formed integral with the lower end of the hopper 2, and in order to counteract the tendency of the pulverized material which works in between the ends of the 105 drum and its bearings to grind away the

bearings and ends of the drum, the latter are each provided with a plurality of independent peripheral grooves 9. Each bearing 8 engages only a portion of the periphery of 5 the corresponding end of the drum, the construction being such that any of the pulverized fuel which finds its way into the grooves 9 at the upper side of the drum will simply be carried around in the rotation of 10 the drum and escape at the discharge side of the drum. In this manner the grinding action of said material upon the bearings and ends of the drum is reduced to a minimum.

15 The drum 5, instead of being provided with a single continuous groove, as in the ordinary screw-conveyor, is provided in its peripheral surface with a series of independent grooves 10 which extend longitudinally 20 of the drum, but in a direction diagonal to its axis. It will be seen that, with this construction, as the drum rotates, each independent groove 10 will be gradually filled from end to end with material from the 25 hopper, and then, in the further rotation of the drum, will gradually empty its load at the discharge side of the drum, whereas, if the grooves were arranged parallel to the axis of the drum, each groove would be filled 30 simultaneously from end to end with material from the hopper and would discharge its entire load at substantially the same instant. The present construction, therefore, insures a substantially uniform feeding of 35 the material from the hopper into the air line and obviates any danger of "flushing." Moreover, the provision of the independent diagonally arranged grooves prevents "flushing" when the rotation of the drum is 40 stopped.

Owing to the relatively large peripheral area of the feeding drum with its series of independent grooves, the said drum can be rotated at a comparatively low speed, thereby enabling a small power consumption. For driving the drum, a small electric motor 11 is provided, which is attached to one 45 end of the casing 1, as indicated in Figure 2, and drives the drum through the pinion 50 12, gear 13, pinion 14 and gear 15.

The main air supply conduit is represented by the reference numeral 16. The conduit 16 communicates at its lower end with a hollow coupling member 17. A burner 18 55 is connected at one end to an end of the coupling member 17, and at its other end projects into the opening 19 in a wall of the furnace 20.

Branching off from the main conduit 16 60 at the point 21 is an auxiliary air conduit 22. This auxiliary air conduit 22 includes a section 23 of the housing 1 arranged to carry the auxiliary air supply past and in contact with the discharge side of the rotatable drum 65 5 and in a direction parallel to the axis of

the drum. The section 23 is provided with a cleaning opening closed by a screw plug 24. A suitable valve 25 is provided in the conduit 22 for regulating the auxiliary air supply.

70 The section 23 has formed at one end thereof an integral flange 26, and clamped between this flange 26 and a ring 27 by means of bolts 28 is an annular metal diaphragm 29. The peripheral edge portion of the diaphragm 29 is clamped between a flange 30 formed integral with one end of the coupling member 17 and a ring 31 secured to the flange 30 by bolts 32, a packing member 33 being interposed between the ring 31 and 75 diaphragm 29. Threadedly connected at one end to the ring 27 and projecting into the coupling member 17 is a pipe 34 forming an extension of the conduit 22. The construction just described provides a flexible and 80 adjustable connection between the main air conduit and the discharge end of the auxiliary air conduit, so as to take care of any slight inaccuracies of alignment between the fuel feeding apparatus and the furnace. 85 When it is desired to adjust the discharge end of the auxiliary conduit with respect to the main air conduit, this can be done by loosening the nuts on the bolts 32 so as to 90 permit shifting of the diaphragm 29 in its own plane, after which the nuts will be tightened again.

95 In the operation of the apparatus, the individual grooves in the rotating drum are 100 gradually filled with material from the hopper and gradually discharge this material into the auxiliary air conduit at the discharge side of the drum. Since the auxiliary air supply sweeps past the drum in a direction substantially parallel to the length of 105 the grooves, the tendency of the auxiliary air supply is to clean the grooves of fuel and fill them with air, which is carried around in the grooves to aerate the fuel in the hopper. Since the discharge end of the auxiliary 110 conduit 22 projects into the coupling member 17, the main air supply has an ejector action upon the auxiliary air supply and the fuel carried in suspension therein, thereby further insuring against "flushing." 115

I claim:—

1. In apparatus for feeding pulverized fuel, an auxiliary air conduit, means for feeding fuel into said conduit, a main air conduit, an extension detachably secured to 120 said auxiliary conduit and projecting into the main conduit, a flexible annular diaphragm secured between flanges on the adjacent ends of said auxiliary conduit and extension, and means adjustably clamping 125 said diaphragm to said main conduit, substantially as described.

2. In apparatus for feeding pulverized fuel, an auxiliary air conduit, a source of 130 fuel supply, a rotatable drum having a series

of independent fuel receiving grooves in its periphery extending longitudinally thereof but in a direction diagonal to its axis for continuously and uniformly feeding material 5 from said source of supply into said auxiliary conduit, and a main air conduit, the auxiliary air conduit being arranged to direct the air in contact with the discharge side of said drum in a direction longitudinally 10 thereof and throughout substantially the length thereof and having its discharge end projecting into said main air conduit, whereby the main air supply acts as an ejector for the auxiliary air supply and the material held in suspension therein, substantially as described. 15

3. In apparatus for feeding pulverized fuel, an auxiliary air conduit, means for feeding fuel into said auxiliary conduit, a main air conduit, the auxiliary conduit communicating at its discharge end with the main air conduit, and a flexible and adjustable connection between the main air conduit and the discharge end of the auxiliary air conduit, substantially as described. 20 25

In testimony whereof I have hereunto set my hand.

HENRY MUELLER.
